WALLET PROTECTOR

Elmer B. Schick, Lexington, Mich.

Application November 9, 1956; Serial No. 621,416

1 Claim. (Cl. 24—3)

This invention has reference to a device adapted for attachment to an otherwise conventional wallet, and so designed as to make it difficult, if not completely impossible, for one to lose his wallet accidentally or have it stolen from the pocket.

A wallet of the type having a transverse fold intermediate its ends is conventionally folded and inserted in one hip pocket. In these circumstances, it sometimes happens that the wallet will tend to slip out of the hip pocket, as for example, when one is in a seated position, or is, perhaps, indulging in physical exercise. In other circumstances, one's pocket may be picked, and in this situation, the wallet is removed without knowledge on the part of the owner of the wallet.

In view of the above, it is proposed in carrying out the invention, to provide a wallet protector having end portions projecting beyond the opposite longitudinal edges of the wallet, with said end portions being adapted to engage opposite walls of the pocket in a manner such that the wallet will be held not only against accidentally slipping out of the pocket, but also, will bind within the pocket should an attempt be made to extract the same without the owner's knowledge.

Another object is to provide a wallet protector of the character described that can be manufactured at a very low cost, and can be embodied in any of various types of conventional wallets of the type inserted in one's hip pocket.

Still another object is to form a wallet protector in such a manner that it can be readily grasped and flexed to a position in which it will no longer bind the wallet within the pocket. In this connection, the flexure of the protector to such position, while being accomplished readily by the owner, is so designed as to prevent the flexing action from being carried out without full insertion of one's hand into the pocket and an accompanying exertion of a positive force tending to flex the protector. In this way, obviously, one attempting to steal the wallet by adjusting the protector to a pocket disengaging position would not be able to do so without the owner becoming fully aware of the attempted theft.

A further object is to provide a wallet protector as described which not only can be used on various types of makes of wallets, but further, can be engaged with said wallets with little or no modification or redesign of the wallet.

Another object is to provide a protective device for insertion in one's pocket which will be adapted for binding within the pocket against accidental loss or theft, not only wallets but any other articles that are insertable in the pocket to which articles the device can be attached. In other words, it is proposed that the wallet protector be designed to engage in the pocket any article to which it can be connected.

Another object is to provide a protective device of the character described that can be manufactured at an extremely low cost, and will not detract from the appearance of the wallet to which it is secured.

Other objects will appear from the following description, the claim appended thereto, and from annexed drawing, in which like reference characters designate like parts throughout the several views, and wherein:

5 Figure 1 is a perspective view showing the device as it appears when binding the wallet against unauthorized removal of the wallet from one's pocket;

Figure 2 is an enlarged perspective view of the open wallet with the protector connected thereto;

10 Figure 3 is a detailed sectional view, still further enlarged, transversely through the protector substantially on line 3—3 of Figure 2;

Figure 4 is a top plan view of the protector per se;

15 Figure 5 is an edge elevational view of the protector per se; and

Figure 6 is an enlarged transverse sectional view on line 6—6 of Figure 5.

Designated generally at 10 is a conventional wallet. The wallet illustrated is of the folding type, and is in 20 association with a protector 12 formed in accordance with the present invention.

The wallet includes the usual laminations 13, 14 and these may be of any desired number. The device can, in fact, be used with the type of wallet having accordion

25 25 Designated generally at 10 is a conventional wallet. The wallet illustrated is of the folding type, and is in association with a protector 12 formed in accordance with the present invention.

The wallet includes the usual laminations 13, 14 and these may be of any desired number. The device can, in fact, be used with the type of wallet having accordion

25 25 Designated generally at 10 is a conventional wallet. The wallet illustrated is of the folding type, and is in association with a protector 12 formed in accordance with the present invention.

Protector 12 comprises two main components, one of

30 30 these being a main strip 22 which is formed from a length of flat, thin spring material. The main strip, and in fact the entire device, can be faced with leather or otherwise ornamentally surfaced as desired, so as to blend with the finish of the wallet.

35 The main strip 22, medially between its ends, is narrowed in width as in 24, that is, the main strip tapers gradually in width from each end toward its mid-length point, as best shown in Figure 4. At its opposite ends, the main strip is rounded, to prevent damage to the side

40 40 walls of the pocket P in which the wallet 10 would normally be disposed (see Figure 1).

Overlying the main strip is a connecting strip 28 which is used to hold the main strip and wallet in assembled

45 45 relation. The connecting strip is of a width approximately equal to the minimum width of the main strip (see Figure 4), and at one end has a rounded end portion 30, the side edges of which merge into the walls of transversely aligned, small notches 31 formed in the opposite side edges of the connecting strip. A narrow

50 50 clip or staple 32 extends transversely of the connecting strip, with the legs of the staple extending through the notches 31 (see Figure 6) and being then extended through openings 33 formed in the main strip in substantial registration with the notches 31. The legs of

55 55 the clip or staple are crimped under the main strip, so as to hold the main and connector strips against movement at the location of the clip.

The clip 32 is disposed substantially medially between one rounded end of the main strip and the narrow mid-length portion of said main strip. Similarly disposed

60 60 between the other end of the main strip and the narrow portion is an oblong slot 34 formed in the main strip. At the corresponding end, the connector strip 28 has a rounded head 36, the side walls of which merge into recesses 38 deeper than the notches 31. The recesses

65 65 65 define a neck 39 on the connector strip adjacent the head 36, which neck is narrower than the slot 34 as shown in Figure 4.

By reason of this arrangement, in assembling the connector and the main strips, the head 36 may first be

70 70 inserted through the slot 34, with the strips in perpendicularly related planes. Thereafter, with the head in

serted and underlying the main strip as shown in Figure 5, the connector strip can be turned 90 degrees about an axis extending longitudinally thereof, so as to now be in superposed relation to the main strip, in the relative position of the strips shown in Figure 5. Thereafter, the clip 32 may be clinched as in Figure 6, to complete the connection.

It will be understood that this connection would not be made until the main strip has been extended between the superposed laminations 13, 14 of the wallet. In other words, the main strip is first extended transversely through the wallet adjacent fold line 20 as shown in Figures 2 and 3. The main strip is of a length substantially greater than the width of the wallet, so that the rounded end portions 26 project substantial distances outwardly laterally from the opposite sides of the wallet, as shown in both Figures 1 and 2. Thereafter, the connector strip, with lamination 13 disposed between the strips, is connected to the main strip in the manner previously described.

Both strips are preferably of springable material, and are highly flexible so as to permit the main strip to be flexed into a pronounced arcuate shape whenever the wallet is to be removed by the owner. In this way, the overall distance between the ends is reduced, so that the wallet can be readily slipped out of the pocket. However, the flexing of the main strip in this manner obviously requires that one insert his hand fully into the pocket, and insert a positive force upon the projecting ends of the main strip. While this can be done with ease by the owner, it is obvious that it could not be done by a pick-pocket, without the owner being made aware of the attempted theft. The main strip is also flexed at the time the wallet is being inserted into the pocket and after insertion, tends to return to a substantially flat or slightly curved shape as shown in Figure 5, causing the rounded ends 26 to bind against opposite side edges of the pocket to prevent unauthorized removal or accidental loss of the wallet.

It may be noted that when the main strip is flexed for insertion or removal of the wallet, the connecting strip has a limited sliding connection, provided by the head 36, neck 38, and slot 34, to the main strip, facilitating flexing of the main strip for the purpose of permitting the insertion or removal of the wallet.

It is believed apparent that the invention is not necessarily confined to the specific use or uses thereof described above, since it may be utilized for any purpose

to which it may be suited. Nor is the specific construction illustrated and described, since such construction is only intended to be illustrative of the principles, and the means presently devised to carry out said principles, it being considered that the invention comprehends any minor change in construction that may be permitted within the scope of the appended claim.

What is claimed is:

A protective device connectable to an article for binding the article against unauthorized removal or loss from the pocket, comprising an elongated strip engageable with the article and adapted at its opposite ends beyond the respective sides of the article for binding against the side walls of the pocket, said strip being of resiliently flexible material and normally flexing to a substantially straight position, said strip being flexible to a curved condition to permit removal from the pocket; and a second strip for connecting the first strip to said article, said second strip terminating at both ends well inwardly from the corresponding ends of the first strip, said second strip being fixedly connected at one end to the first strip and having a sliding connection at its other end to the first strip, said sliding connection being arranged to limit the strips to sliding movement longitudinally of each other, said sliding connection comprising a flat head on the second strip at the base of which head said second strip has a neck reduced in width relative to the width of the portions of the second strip contiguous thereto, the first strip having a longitudinal slot greater in width than said neck but smaller in width than the maximum width of the head, the slot being greater in length than the width of the head to permit insertion of the head therethrough, said head lying in face-to-face, sliding engagement with one face of the first strip, said neck extending through the slot with the remainder of the first strip overlying the opposite face of the first strip.
